(57) **CLAIM**

The ornamental design of a carabiner, as shown and described.

DESCRIPTION

FIG. 1 is a front perspective view of a carabiner in accordance with the present invention, with the portions shown in broken lines included for illustrative purposes only and forming no part of the claimed design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front perspective view of a second embodiment of the carabiner in accordance with the present invention, with the broken lines depicting portions of the carabiner that form no part of the claim;

FIG. 9 is a front view of FIG. 8;

FIG. 10 is a rear view of FIG. 8;

FIG. 11 is a top view of FIG. 8;

FIG. 12 is a bottom view of FIG. 8;

FIG. 13 is a left side view of FIG. 8;

FIG. 14 is a right side view of FIG. 8;

FIG. 15 is a front perspective view of a third embodiment of the carabiner in accordance with the present invention, with the broken lines depicting portions of the carabiner that form no part of the claim;

FIG. 16 is a front view of FIG. 15;

FIG. 17 is a rear view of FIG. 15;

FIG. 18 is a top view of FIG. 15;

FIG. 19 is a bottom view of FIG. 15;

FIG. 20 is a left side view of FIG. 15;

FIG. 21 is a right side view of FIG. 15;

FIG. 22 is a front perspective view of a fourth embodiment of the carabiner in accordance with the present invention, with the broken lines depicting portions of the carabiner that form no part of the claim;

FIG. 23 is a front view of FIG. 22;

FIG. 24 is a rear view of FIG. 22;

FIG. 25 is a top view of FIG. 22;

FIG. 26 is a bottom view of FIG. 22;

FIG. 27 is a left side view of FIG. 22;

FIG. 28 is a right side view of FIG. 22;

FIG. 29 is a front perspective view of a fifth embodiment of the carabiner in accordance with the present invention, with the broken lines depicting portions of the carabiner that form no part of the claim;

FIG. 30 is a front view of FIG. 29;

FIG. 31 is a rear view of FIG. 29;

FIG. 32 is a top view of FIG. 29;

FIG. 33 is a bottom view of FIG. 29;

FIG. 34 is a left side view of FIG. 29;

(Continued)

FIG. 35 is a right side view of FIG. 29;
 FIG. 36 is a front perspective view of a sixth embodiment of the carabiner in accordance with the present invention, with the broken lines depicting portions of the carabiner that form no part of the claim.
 FIG. 37 is a front view of FIG. 36;
 FIG. 38 is a rear view of FIG. 36;
 FIG. 39 is a top view of FIG. 36;
 FIG. 40 is a bottom view of FIG. 36;
 FIG. 41 is a left side view of FIG. 36; and,
 FIG. 42 is a right side view of FIG. 36.
